[57] **CLAIM**

The ornamental design for an insulative electrical connector cover for z-shaped connector, as shown and described.

DESCRIPTION

FIG. 1 is a perspective view of the design for an insulative electrical connector cover for a z-shaped connector, depicting the front, top and right side thereof;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and,

FIG. 7 is a bottom elevational view thereof.

FIG. 1

FIG. 2

FIG. 3

FIG. 4

FIG. 5

FIG. 6

FIG. 7
